United States Patent Office

Des. 200,113
Patented Jan. 19, 1965

200,113

CLOCK OR SIMILAR ARTICLE

William V. Judson, Westport, and Walter C. Anderson,
Southport, Conn., assignors to General Electric Com-
pany, a corporation of New York

Filed Jan. 27, 1964, Ser. No. 78,383

Term of patent 7 years

(Cl. D42—7)

Fig. 1.

Fig. 2.

Fig. 3.

Fig. 4.

Fig. 5.

FIG. 1 is a front perspective view of a clock embodying our new design;

FIG. 2 is a front elevational view of the clock shown in FIG. 1;

FIG. 3 is a rear elevational view of the clock shown in FIG. 1;

FIG. 4 is a top plan view of the clock shown in FIG. 1; and

FIG. 5 is a side elevational view of the clock shown in FIG. 1.

The essential features of our design are shown in full lines.

We claim:

The ornamental design for a clock or similar article, substantially as shown and described.
